UNITED STATES PATENT OFFICE.

FRANK BEAN, OF MEDFORD, MASSACHUSETTS.

SEWING-MACHINE.

SPECIFICATION forming part of Letters Patent No. 309,516, dated December 23, 1884.

Application filed November 19, 1883. (Model.)

To all whom it may concern:

Be it known that I, FRANK BEAN, a citizen of the United States, residing at Medford, in the county of Middlesex and State of Massachusetts, have invented certain new and useful Improvements in Sewing-Machines, of which the following is a specification.

My invention relates to that class of sewing-machines in which the stitch is formed by a single thread drawn through the work by a hook; and it has for its objects so constructing the machine that the position of the presser-foot as it varies with the thickness of the work regulates the length of motion of the thread-drawing hook, and that the operator may change the length of stitch while the machine is in motion by means of a foot-lever. I attain these objects by the mechanism illustrated in the accompanying drawings, in which Figure 1 is a front elevation of my machine. Fig. 2 is a sectional view on line $y-y$ of Fig. 1, showing the feed-adjusting device. Fig. 3 is a side elevation. Fig. 4 is a horizontal section on line $x-x$, Fig. 3. Fig. 5 is an elevation 25 of parts that show immediately behind the line $z-z$, Fig. 3. Fig. 6 is an elevation showing parts that relate immediately to the device for transmitting motion from a cam-groove to the presser-foot, being a modification of the device shown in Fig. 8. Fig. 7 is a detail. Fig. 8 is an elevation showing parts immediately behind the line $v-v$ of Fig. 3. Fig. 9 is a horizontal section on line $w-w$, Fig. 8. Fig. 10 is a perspective view of a shoe to illustrate the difference of the length of stitch in the shank and ball, also to show the varying thickness of the sole.

My machine, in its general operation and method of sewing, is the same as the ordinary single-wax-thread machine, and most of the parts are constructed substantially as in the ordinary manner. Therefore I do not consider it necessary to fully describe all of its parts and their operations.

Let B, Fig. 1, represent the awl; B', awl-carrier; B², an arm on the shaft B³ for actuating the awl-carrier, said shaft B³ being operated by the arm B⁴, face-cam B⁵, and cam-pin B⁶. (See Fig. 3.) D, Fig. 1, is the thread-carrier,

which is operated by the rack and pinion D' 50 D², Fig. 4.

C, Fig. 1, is the presser-foot and its rod, made in the usual manner. This presser-foot is actuated by the cam-disk C¹⁰, Figs. 3 and 8. The cam-groove C¹, acting on the cam-pin C⁸, 55 causes the lever C⁵ to swing on its fixed pivot C⁶, Fig. 8. This motion of the lever C⁵ is communicated through a toggle-clamp, e³, to a swinging block, e², thence to the flattened rod e, thence through the arm C³ to the rocker-shaft C², Fig. 8. From the rocker-shaft C², Fig. 3, motion is communicated to the presser-foot C by means of a slotted arm, C', and a pin, p. (See Fig. 1.)

By the devices shown in Figs. 6 and 8 I am 65 enabled to cause the presser-foot C to rise a fixed distance above the stock being worked, irrespective of its thickness. For instance, the distance the presser-foot shall rise and fall is determined by the shape of the cam, Figs. 6 and 8—say one-fourth of an inch—the operating-lever C⁵ passing through that distance at every revolution of the cam C¹⁰, and as the rod e, Fig. 8, is not held by the clamping-toggle e³ except when the lever C⁵ is rising, it 70 may be seen that the rod e may be moved irrespective of the lever C⁵. Thus, if thick stock 75 is placed under the presser-foot, the presser-foot will rest at a distance above the needle-plate of the machine equal to the thickness of 80 the stock, and acting through the arm C', rocker-shaft C², and arm C³, Fig. 8, will hold the rod e up, so that the rod e occupies a position when at rest exactly corresponding 85 with the position of the presser-foot—that is, in a position elevated or depressed corresponding to the thickness of the stock. Now, if we examine the clamping device at e³, Fig. 8, we shall see that in the upward movement of the lever C⁵ the rod e is taken from its position, 90 already determined by the thickness of the stock, and raised to a position above it equal to the full throw of the cam-groove C¹.

The object of giving the presser-foot a uniform movement above the stock is to obtain a 95 motion regulated by the thickness of the stock that may be transmitted to the hook h, so that the vertical movement of the hook shall be

more or less as the stock being sewed increases or decreases in thickness, it being evident that to do good work more length of thread must be used for each stitch in thick work than would be required in thin work.

My device for regulating the motion of the hook h by the presser-foot C consists of an arm, F , attached to the rocker-shaft C^2 , link F' , link F^2 , provided with a pin, F^3 , which 10 slides in a slot made in the lever F^4 , Figs. 1 and 5, the lever F^4 being operated by the cam-groove F^6 , which acts upon the pin F^7 . The motion given to the slotted lever F^4 , Fig. 5, is a determined motion about the center F^5 ; but 15 the motion it transmits to the link F^2 is a variable motion, it being greater when the pin F^3 is moved upward in the direction of the arrow T and less when it is moved in the opposite direction, and as the position of the pin 20 F^3 is governed by the presser-foot mechanism it is evident that the variation in motion of the link F^2 is governed by the position of the presser-foot C —that is, if the presser-foot is raised by the stock it will cause the rocker-shaft C^2 to revolve in the direction of the arrow T' , and thus cause the arm F , acting 25 through the link F' , to draw the pin F^3 up the slot in the direction of the arrow T , thus increasing the motion of the link F^2 . The motion of the link F^2 is transmitted to the hook h by the arm H , rocker-shaft H' , Fig. 5, arm H^2 , pin H^3 , and sliding bar H^4 , Fig. 1. In Fig. 6 I have shown a modification 30 of the device shown in Fig. 8 for regulating the motion of the presser-foot. In this case the arm C^2 has, instead of the rod e , a mortised link-piece, C^4 , which serves to connect it with the lever C^5 . Immediately above the end of the lever C^5 , that enters the mortise in the lever C^4 , I place a wedge, E^3 , said wedge being connected by a shank-piece, E' , to an arm, E , which projects from the rocker-shaft C^2 . This wedge E^3 presents a thick or thin part between the end of the lever C^5 45 and a friction-block, E^4 , Fig. 7, placed in the mortise of the link C^4 , in accordance with the position of the arm E and rocker-shaft C^2 , which position is determined, as has already been explained, by the thickness of the work 50 under the presser-foot.

It being desirable to use stitches of different lengths in sewing shoes, I have invented the following device for the purpose of enabling the operator to change the length of stitch by simply depressing the foot-lever L^3 , Fig. 1. This can be done without stopping the machine or interfering with its work.

K' , Fig. 2, is a rocker-shaft operated by an ordinary cam motion, and has upon its end a slotted arm, K^2 , the slot being represented by K^3 .

K^8 , Figs. 1, 2, and 3, is a horizontally-sliding housing which holds the reciprocating bar H^1 of the hook h . This housing K^8 slides horizontally in dovetail grooves. (Represented at k 65 k , Fig. 2.)

K^5 K^6 represent a bolt or stud attached to the sliding housing K^8 in such a manner that it may slide vertically in the said housing, the part L , Fig. 2, being rigidly attached to the 70 stud K^5 , but free to slide vertically in the housing.

L' is a projection on the piece L , and serves to connect the piece L by means of the rod L^2 to the foot-lever L^3 . The inner end, K^4 , of the 75 stud K^5 rests in the slot K^3 of the swinging arm K^2 .

R R , Fig. 2, are adjusting-screws which limit the vertical motion of the stud K^5 . As the length of the stitch depends upon the 80 throw of the stud K^5 , it is evident it will be longer when the stud K^5 is drawn down toward the lower end of the arm K^2 , and shorter when it is allowed to rest in a higher position.

S , Fig. 1, is a spring which throws the piece 85 L and the stud K^5 upward when it is not forced downward by the lever L^3 . In working this machine the ordinary length of stitch is determined by the upper adjusting-screw, R ; but when the operator wishes to lengthen the 90 stitch he places his foot upon the lever L^3 and draws the stud K^5 down.

In Fig. 10 I have shown a shoe sole side up, for the purpose of showing the length of the stitches, but in sewing the shoe its position is 95 reversed—that is, the sole side is down and the welt upward.

I claim as my invention—

1. In a sewing-machine, the combination of the presser-foot bar C and its operating mechanism, consisting of the arm C' , rock-shaft C^2 , arm C^3 , and rod e , with the cam mechanism for operating the same, consisting of the cam C^0 , cam-groove C^1 , lever C^5 , and clamping mechanism e^3 e^2 , operating together substantially as described, and for the purpose set forth. 100

2. In a sewing-machine, the combination of the rock-shaft C^2 , the arm F , link F' , and the slotted lever F^4 , with the cam-pin F^7 , cam F^8 , 110 cam-groove F^6 , link F^2 , having pin F^3 , arm H , rock-shaft H' , arm H^2 , rod H^4 , hook h , and complementary means, as described, for completing a stitch, all working together substantially as described, and for the purpose set 115 forth.

FRANK BEAN.
